UNITED STATES PATENT OFFICE.

HENRY F. STOCK, OF WAUKESHA, WISCONSIN, ASSIGNOR TO LADEWIG & STOCK COMPANY, OF WAUKESHA, WISCONSIN, A CORPORATION OF WISCONSIN.

BOTTLE-WASHING MACHINE.

1,182,597.

Specification of Letters Patent.

Patented May 9, 1916.

Application filed November 14, 1913. Serial No. 300,895.

To all whom it may concern:

Be it known that I, HENRY F. STOCK, a citizen of the United States, residing at Waukesha, in the county of Waukesha and 5 State of Wisconsin, have invented certain new and useful Improvements in Bottle-Washing Machines, of which the following is a specification, reference being had to the accompanying drawing, forming a part 10 thereof.

This invention relates to bottle washing machines and the objects of the invention are to improve bottle washing machines in the manner to be fully described in this 15 specification and to be specifically pointed out in the claims annexed hereto.

Referring to the drawings which accompany this specification and form a part hereof, which drawings illustrate an embodiment 20 of this invention, and on which drawings the same reference characters are used to designate the same elements wherever they may appear in each of the several views, Figure 1 is an elevation of one side of the 25 machine; Fig. 2 is an elevation of the other side of the machine; Fig. 3 is a sectional elevation of the machine taken on the line *a—a* on Fig. 2, looking in the direction indicated by the arrows; Fig. 4 is a plan view of 30 details of construction; Fig. 5 is a longitudinal, vertical section of a combined water and air valve; Fig. 6 is a vertical, transverse section of the same taken on the line *b—b* on Fig. 5; Fig. 7 is an elevation, partly in section, and with parts broken away, of details 35 of construction; Fig. 8 is an elevation of details of construction, parts being broken away; and Fig. 9 is an elevation, partly in section, and with parts broken away, the 40 section being taken on the line *c—c* on Fig. 8.

Referring specifically to the drawings, the machine is assembled on a suitable frame 1. The frame 1 supports four shafts 2, 3, 45 4 and 5 upon which are sprocket wheels 6, 7, 8, 9, 10, 11, 12 and 13 upon which the endless chains 14 and 15 travel to carry the bottles to be washed. These chains are preferably of the roller type and are composed of 50 rollers 16, axles 17, plain links 18 and special links 19. The special links 19 have projecting lugs 20 to which are secured bars 21 and a plurality of bottle supports 22 to compose separate bottle carriages. The bottle 55 supports 22 are funnel-shaped and may be

lined with rubber cushions to protect the bottles. The chains 14 and 15 with the bottle carriages constitute a conveyer for the bottles. This conveyer is moved forward intermittently in a step-by-step movement by 60 the spring-pressed pawl 23 which works with the ratchet wheel 24 secured to shaft 2. Pawl 23 is pivotally mounted upon rocker 25 which is loosely supported on shaft 2 and rocked by link 26 connected to crank 27 on 65 shaft 28.

Shaft 29 is the power shaft which operates the machine. It is provided with a worm 30 which drives worm wheel 31 on shaft 32, on which is spur gear 33 meshing 70 with gear 34 on shaft 35. Shaft 35 drives shaft 28 by means of the gears 36 and 37.

On shaft 2 is a lock plate 38 in the nature of a double acting ratchet wheel with the notches in which a pawl 39, pivoted to the 75 frame 1, engages to prevent movements of the conveyer in either direction when unsymmetrically loaded with bottles and while the conveyer is intended to remain at rest. Pawl 39 is engaged with a notch in the lock 80 plate 38 at all times except when released to permit a forward movement of the conveyer and, consequently, pawl 39 must have a timed release with the working movement of pawl 23. To effect such timed release, a 85 crank 40 is secured to shaft 28 and is provided with a pin 41 adapted to contact with and elevate the free end of a lever 42 pivoted to the frame 1. A link 43 connects lever 42 and pawl 39 to lift the weight 44 and 90 rock the pawl about its pivot in a manner which will be readily understood from an inspection of Fig. 1 of the drawings.

Inclines 45 and 46 are provided at the loading end of the machine and other inclines 47 and 48 are provided at the unloading end of the machine to lead the conveyer at convenient angles for supplying bottles thereto or removing bottles therefrom and track members, designated by the reference 100 character 49, are provided for the rollers of chains 14 and 15 to preserve the alinement of the chains, to prevent vibrations and to take the loads and strains off from the sprocket wheels and their shafts.

The inclines 45 and 46 at the loading end of the machine lead the conveyer at a convenient angle for feeding bottles by hand or by any suitable automatic feeding mechanism to the conveyer and the inclines 47 and 110

48 at the unloading end of the machine lead the conveyer at a convenient angle for removing the bottles from the machine by hand. If desired, however, the bottles may 5 be discharged automatically from the machine by arranging any suitable device to receive the bottles as they pass with the conveyer from a position in which they are retained in the bottle supports 22 to a position 10 where they will slide out of the bottle supports 22.

The reference numeral 221 designates a device to receive the bottles as they are automatically discharged from the conveyer and 15 the device, as shown, comprises an inclined plate on which the bottles are received and from which they may be permitted to slide into any suitable receptacle or from which they may be removed in any suitable manner 20 by hand or mechanism.

The machine is primarily intended for washing and cleansing the interiors of bottles and the bottles are inserted, with their necks down, in the individual bottle supports 22. The bottles are moved forward intermittently by the step-by-step movements of the conveyer and in certain positions, and while the bottles are at rest, the bottles are centered and clamped, nozzles 30 (and brushes, if desired) are inserted in bottles, the washing and cleansing agent, or agents, is admitted to bottles for a period, the nozzles are then withdrawn from the bottles, the bottles are unclamped and the 35 pawl 23 moves the conveyer forward another step for another cleansing operation.

With the machine, as illustrated, each bottle may be subjected to the washing or cleansing operation three times, or only two 40 times as later described, but, of course, the number of times the bottles are subjected to the washing or cleansing operation is merely a matter of selection and convenience. Ordinarily bottles are soaked before being 45 washed and cleansed on the machine and I find in practice that two washings, or the use of two sets of nozzles, is all that is necessary to thoroughly cleanse bottles no matter how dirty they may be. The preceding 50 statement is, of course, intended to apply only to beer, mineral water and such bottles and not to bottles which have contained oils, gums or such substances as cannot ordinarily be washed away by water.

55 The bottle clamping mechanism, as shown for operating upon three rows of bottles at a time, consists of three upper cross beams 50, 51 and 52 and three lower cross beams 53, 54 and 55. The lower cross beams are hung 60 by links 56, 57, 58, 59, 60 and 61 from horizontal beams 62 and 63 which in turn are hung by links 64, 65, 66 and 67 from levers 68, 69, 70 and 71 which are pivotally supported from the frame 1. These levers are 65 provided with counter-weights 72, 73, 74 and

75 and nut-holder beams 76 and 77 are suspended from them by links 78, 79, 80 and 81. Screws 82, 83, 84 and 85 engage with nuts secured to the nut-holder beams and support the upper cross beams 50, 51 and 52 by 70 means of the tie-beams 86 and 87. The screws 82, 83, 84 and 85 are rotatable with respect to the tie-beams 86 and 87 so as to move said tie-beams and the upper cross beams 50, 51 and 52 secured thereto and carried thereby toward or away from the nut-holder beams 76 and 77 to adjust the clamping mechanism to bottles of different lengths as pints and quarts, for example. The 75 screws 82, 83, 84 and 85 can be rotated in unison by the hand wheel 88 through the shafts 89 and 90, sprocket wheels 91 and 92, sprocket chain 93, and gears 94, 95, 96, 97, 98, 99, 100 and 101 in a manner which will be

readily understood from an inspection of the drawings. Because the upper cross beams 50, 51 and 52 and the lower cross beams 53, 54 and 55 of the clamping mechanism are connected to the levers 68, 69, 70 and 71 on opposite sides of their fulcrum points, the upper cross beams will always move in the direction opposite to the movement of the lower cross beams. In other words, these two sets of beams will either approach each other or recede from each other, the action 80 being similar to the opening and closing movements of the jaws of a pair of pliers having parallel movements of the jaws. Thus the upper and lower cross beams constitute clamping jaws between which the 85 bottles are clamped and securely held while 90 they are being washed or cleansed. As bottles are fragile and are apt to differ slightly in length even when they are of the same market size, as quarts for example, the upper cross beams are provided with depending fingers 102 which are free to move up and down with respect to the cross beams and are yieldingly held in their lowermost 95 positions by spiral springs 103. The lower 100 cross beams carry funnel-shaped centering and clamping cups 104 through which the nozzles are guided and these cups are yieldingly supported by spiral springs 105. The 105 counter-weights 72, 73, 74 and 75 close the 110 clamping jaws, composed of the upper cross beams 50, 51 and 52 and the lower cross beams 53, 54 and 55, with the yieldable fingers 102 and the yieldable cups 104, upon the 115 bottles so that the bottles are cushioned 120 while the bottles are held between clamping jaws which are not clamped upon the bottles by any power-driven mechanism of the machine whereby the danger of breaking the 125 bottles is obviated.

In the machine illustrated the clamping mechanism is adapted to clamp three rows of bottles at a time and in starting the machine as the bottles first reach the clamping mechanism only one row of bottles will be 130

in position to be clamped. This same condition might also happen when the machine is being operated and by accident one or more bottle carriages had not been supplied with 5 bottles. Under such conditions, especially if the upper cross beams 50, 51 and 52 were somewhat loose on their guides, a cross beam which was not supported by bottles might drop far enough to cause the cross beam to 10 bind on its guide. To avoid such a result and to insure equal movements of the upper cross beams, the pairs of levers 68, 69 and 70, 71 are geared together by the gear segments 222, 223, 224 and 225 at the ends of the 15 respective levers.

The specific construction of the machine, as illustrated by the drawings, is provided with three cleansing-fluid heads 106, 107 and 108 and the middle head 107 is shown as 20 provided with brushes 226 carried by revolute nozzles 109 while the two end heads are not provided with brushes and their nozzles 110 are non-revolute. The cleansing-fluid heads are constructed to supply both water 25 and compressed air to the nozzles and consist of two chambered castings 111 and 112 bolted together with a diaphragm 113 between them. The nozzles are slidably retained in tubular standards 114 closed by 30 caps 115 against which the collars 116 on the nozzles are yieldingly held by springs 117. It sometimes happens that a bottle is placed on the machine with its stopper in 35 place or with some hard object in a bottle so that a nozzle cannot enter the bottle and the construction described prevents breakage of a nozzle because if for any reason the upward movement of a nozzle is arrested its tubular standard 114 can still move upward 40 to its extreme limit of movement while the nozzle remains stationary and compresses its spring 117.

The diaphragms 113 are provided with eduction nozzles 118 to mix air from air 45 chambers 119 with water flowing from water chambers 120. Compressed air is supplied to air chambers 119 and the air not only drives the washing water from the bottles but also agitates the washing water in the 50 bottles thereby facilitating the cleansing of the bottles.

The cleansing-fluid heads 106, 107 and 108 are hung from horizontal beams 121 and 122 by links 123, 124, 125, 126, 127 and 128 and 55 levers 129, 130, 131 and 132 are connected by links 133, 134, 135 and 136 with horizontal beams 121 and 122. Weights 137, 138, 139 and 140 are adjustably secured to 60 said levers for counterbalancing the weight of the cleansing-fluid heads and nozzles, and the levers are keyed, or otherwise secured, to shafts 141 and 142 so as to move in unison. The cleansing-fluid heads and nozzles are raised to insert the nozzles in bottles 65 by the crank 143 on shaft 35 which rocks

shafts 141 and 142 by means of the connecting rods 144 and 145 and cranks 146 and 147. The crank pin on crank 146 is received in a box 148 which is slidable in the bifurcated end of connecting rod 144 and which 70 is adapted to be contacted by the end of the adjustable screw 149 to rock shafts 141 and 142 and lift the cleansing-fluid heads and the nozzles in a manner which will be 75 readily understood from an inspection of the drawings. This construction provides a lost motion connection between connecting rod 144 and crank 146. As the crank 143 is revolving continuously while the machine is in operation, this lost motion connection 80 provides for a period of rest or a dwell of the cleansing-fluid heads when in their lowermost positions and the step-by-step movements of the conveyer and bottles take place during these periods of rest of the 85 cleansing-fluid heads. By adjusting the screw 149 the lift of the cleansing-fluid heads (and the nozzles carried thereby) can be properly proportioned for long or short bottles such as quarts or pints. The bottles 90 are held in a substantially fixed position by the conveyer and the clamping mechanism and by screwing screw 149 in toward block 148 a greater lift is given the cleansing-fluid heads and nozzles while by screwing 95 the said screw out or away from block 148 a lesser lift is given the cleansing-fluid heads and nozzles.

To guard against the cleansing-fluid heads being overbalanced by the counterbalance weights 137, 138, 139 and 140, the effect of which would be to raise the cleansing-fluid heads and nozzles at times when they are intended to remain in their lowermost positions, and to provide for the 100 counterbalance weights 137, 138, 139 and 140 being set far enough out on their levers to balance the weight of the cleansing-fluid heads and the parts carried thereby without possibility of such overbalancing, the 105 abutment 227 is provided in the bifurcated end of connecting rod 144 and a spiral spring 228 is compressed between the said abutment and the block 148 which acts in opposition to the counterbalance weights 110 and in effect loads the cleansing-fluid heads 115 by the amount of the compression of the spring as will be readily understood. The rod 229 which is secured to block 148 and passes through an opening in abutment 227 120 is passed through spring 228 to keep the spring from buckling sidewise. The shafts 141 and 142 are provided with cranks 150 and 151 connected by the connecting rod 152 to guard against torsional strains and 125 possible uneven lifting of the opposite ends of the cleansing-fluid heads.

As hereinbefore explained, the clamping jaws are closed upon the bottles by the 130 weights 72, 73, 74 and 75, but the clamping 130

jaws are opened and said weights are elevated by the descent of the cleansing-fluid heads through the medium of the rods 153, 154, 155 and 156 which pass through holes 5 in the horizontal beams 62 and 63 and are secured to said beams by nuts above and below said beams as clearly shown by the drawings. These rods 153, 154, 155 and 156 also pass through holes in the horizontal 10 beams 121 and 122 and are provided with nuts below said beams only so that said beams can move up on said rods after the upward movement of the rods has been arrested by the fingers 102 and the clamping 15 cups 104 of the clamping jaws coming in contact with bottles. This construction provides a lost motion connection between the clamping jaws and the power driven parts of the machine. Of course the weights 20 72, 73, 74 and 75 cannot close the clamping jaws any faster than the horizontal beams 121 and 122 are lifted and the clamping jaws will be positively opened when the beams 121 and 122 in moving down contact 25 with the nuts on the rods 153, 154, 155 and 156.

Guides 157, 158, 159, 160, 161 and 162 are provided for the upper cross beams 50, 51 and 52, the lower cross beams 53, 54 and 30 55 and the cleansing-fluid heads 106, 107 and 108. Stops 163, 164, 165, 166, 167 and 168 are provided below the cleansing-fluid heads to accurately determine the extent of their downward movement as it is desired to 35 retain the upper ends of the nozzles within the bores of the clamping cups 104 after they have been withdrawn from the bottles. Stops 169, 170, 171 and 172 are located above the lower cross beams 53 and 55 which 40 should be so adjusted that the clamping cups will just touch the mouths of the bottles in theory. In practice, however, the bottles can be lifted a little by the cups without causing them to tip enough in the bottle 45 supports 22 to prevent the fingers 102 from contacting with them properly. Stops 173 and 174 are located below the lower cross beam 54 to support the same if it is disconnected from the horizontal beams 62 and 50 63. The middle, or rotatable set of nozzles, can be cut out of operation if desired by disconnecting the links 57 and 60 of the lower cross beam 54 from the horizontal beams 62 and 63 by the pins 175 and 176 and 55 by disconnecting the links 124 and 127 of the cleansing-fluid head from the horizontal beams 121 and 122 by the pins 177 and 178. When the machine is provided with nozzles which carry brushes, it is sometimes desirable 60 to discontinue the use of the brushes when bottles are to be washed or cleansed which do not require to be brushed.

Valves 179, 180 and 181 control the flow of water and air to the respective cleansing-fluid heads 106, 107 and 108 and through

the nozzles leading therefrom intermittently, timed with the elevated positions of the nozzles, by means of the valve-arms 182, 183 and 184 which are connected by the link 185 and which are operated in unison by 70 lever 132 through link or connecting rod 186 and crank 187. A collar 188 and nut 189 permit movements of the connecting rod 186 in either direction as lever 132 moves. This construction provides a lost motion connection 75 which permits a delayed opening and closing of the valves so that they will not be opened until the nozzles have entered the mouths of the bottles and need not be closed until the nozzles are about to be withdrawn 80 from the mouths of the bottles. By withdrawing pin 190 valve 180 can be cut out of action when the rotatable nozzles and the cleansing-fluid head 107 are cut out of action as hereinbefore described. The valves 85 comprise a casing 191 with air passageway 192 and water passageway 193 and a bore intersecting these passageways which is closed by the heads 194 and 195 within 90 which the valve stem 196 is received. The bore has a shoulder 197 against which a packing collar 198 on the valve stem bears to make a tight joint, the collar being retained against the shoulder by the screw 199 provided with the lock nut 200. Within the 95 passageways are located the valve-closure members 201 and 202 which partially embrace the valve stem and are held against their seats by springs 203 and 204, all as clearly shown by Figs. 5 and 6 of the drawings. 100

In order that the revolute nozzles 109, which are shown as provided with brushes, may be revolved by their tubular standards 114 a clutch mechanism is provided to clutch 105 the standard and its nozzle together under normal conditions because the friction of the brush in a bottle would hold the nozzle stationary while its standard was being revolved unless some such arrangement were 110 provided. Fig. 7 of the drawings illustrates a simple and effective clutch mechanism for this purpose. The upper part of a collar 116 is squared or formed in some other suitable polygonal shape as designated by the reference numeral 230 and a washer 231 with a correspondingly shaped hole is clamped between the cap 115 and the end of the standard 114. This construction permits the nozzle to be unclamped from the 115 standard if the nozzle, in its rising movement encounters an obstruction and is prevented from rising farther. The nozzle might encounter an obstruction within a bottle and the uncoupling of the nozzle from the standard guards against the possibility of breakage. 120

The revolute standards 114 are secured to gears 205 which mesh and are revolved by the gear 206 which is driven by the 130

squared shaft 207. The squared shaft 207 is held against endwise movements and gear 206 slides up and down thereon with the up and down movements of the cleansing-fluid head 107. To produce a more even and easier drive of the revoluble standards and nozzles, the squared shaft 207 and its gear 206 are duplicated at the opposite end of the cleansing-fluid head 107 and these shafts are rotated by gears (not shown) meshing with gears (not shown) on shaft 212 which is driven by gear 213, on shaft 29, shaft 214, sprocket wheel 215, chain 216 and sprocket wheel 217.

Compressed air is led to the valves 179, 180 and 181 by the pipe 208 and water is led to the valves by pipe 209. The air and the water are conducted to their respective chambers in the cleansing-fluid heads from the valves by separate flexible pipe or hose connections some of which show on the drawings and, for convenience, the water hose are designated by the reference numeral 210 and the air hose by the reference numeral 211. A catch basin 218 receives the water discharged from the bottles and this water may flow through an outlet 219 to a receptacle 220 from which it may be conducted to any place desired.

While I have described a specific structure of machine I realize that numerous mechanical changes can be made in some of the mechanisms described and illustrated and I do not limit myself to the specific structures illustrated and described by this specification except where I specifically claim such structures in the claims annexed hereto.

The operation of the machine is as follows: Shaft 29 is continuously revolved from any suitable source of power. Bottles are placed in the bottle supports 22 at the charging end of the machine and removed at the discharging end of the machine. All the shafts and gears driven from shaft 29 are revolving continuously except the shafts and sprocket wheels thereon which carry the endless chain conveyer. Once in every revolution of gear 37 the pin 41 elevates lever 42 and disengages pawl 39 from lock plate 38 and while this pawl is disengaged from the lock plate pawl 23 moves the endless chain conveyer, and the bottles carried thereby, forward one step. During this movement of the conveyer the nozzles are in their lowermost positions, the members of the bottle clamp, or the clamping jaws, are separated and valves 179, 180 and 181 are closed. At the end of this movement pawl 39 engages a notch in lock plate 38, shafts 141 and 142 are rocked thereby raising the cleansing-fluid heads, or permitting them to be raised by the weights 137, 138, 139 and 140, the rods 153, 154, 155 and 156 follow up with the horizontal beams 122 and 123 under the influence of the weights 72, 73, 74 and 75 and the fingers 102 and the centering and clamping cups 104 approach each other until they contact with the bottles in line with them and stop. The cleansing-fluid heads continue to rise and the nozzles enter the mouths of the bottles and the water and the compressed air is admitted to the bottles through the nozzles for the length of time determined by the gearing proportions of the machine. When the cleansing-fluid heads descend the horizontal bars or beams 122 and 123 engage with the nuts on the lower ends of the rods 153, 154, 155 and 156 and elevate the weights 72, 73, 74 and 75 and separate the fingers 102 from the centering and clamping cups 104, or separate the jaws of the clamping mechanism. Assume that the machine as illustrated by the drawings is adjusted for washing quart bottles, and it is desired to change the adjustments to wash smaller bottles, say pint bottles, the hand wheel 88 is turned to screw the tie beams 86 and 87, upper cross beams 50, 51 and 52 and fingers 102 down to provide for the difference in lengths of the bottles and screw 149 is screwed out a sufficient distance to lessen the lift of the cleansing-fluid heads by the difference between the lengths of the bottles as will be readily understood.

What is claimed is:

1. In a bottle washing machine, the combination with upper and lower cross beams provided with yieldable fingers and cups, of an endless chain conveyer provided with bottle supports passing between said cross beams, movable cleansing fluid heads provided with nozzles adapted to be reciprocated through said cups, connections between said cross beams to cause movements thereof simultaneously but in opposite directions, means to separate said cross beams actuated by power-driven mechanism of the machine and means not actuated by power-driven mechanism of the machine to move said cross beams toward each other to clamp bottles therebetween.
2. In a bottle washing machine, the combination with upper and lower cross beams provided with yieldable fingers and cups, of an endless chain conveyer provided with bottle supports passing between said cross beams, movable cleansing fluid heads provided with nozzles adapted to be reciprocated through said cups, connections between said cross beams to cause movements thereof simultaneously but in opposite directions, means to lift said cleansing fluid heads and nozzles, means providing a lost motion connection between the cleansing fluid heads and the lower cross beams to permit movement upward of the cleansing fluid heads after bottles have been clamped between the cross beams, and means for mov-

- ing the cross beams toward each other to clamp bottles therebetween without subjecting the bottles to pressure from power-operated parts of the machine.
5. 3. In a bottle washing machine, the combination with standards provided at their upper ends with clutch members, means for revolving the standards, nozzles provided with clutch members adapted to engage with 10 the clutch members of the standards, and yieldable means adapted to retain the clutch members in engagement and to permit their disengagement.
4. In a bottle washing machine, the combination with a bottle conveyer and movable cleansing fluid heads provided with washing nozzles, of means for raising and lowering said cleansing fluid head, cross beams on opposite sides of the conveyer for clamping bottles, means connecting said cross beams to cause them to move simultaneously but in opposite directions, weights for caus-
- ing said cross beams to approach each other and means operated in unison with the downward movements of the cleansing fluid 25 heads to separate said cross beams from each other.
5. In a bottle washing machine, the combination with cleansing fluid heads provided with nozzles, a step by step operated conveyer for bottles, means for raising the cleansing fluid heads and nozzles which includes a lost motion connection, means for varying the amount of lost motion, means for counterbalancing the cleansing fluid 30 heads and means for preventing overcounterbalancing the cleansing fluid heads.

In witness whereof I hereto affix my signature in presence of two witnesses.

HENRY F. STOCK.
